UNITED STATES PATENT OFFICE.

CLARK L. BRAUCHER AND EDWARD R. JOHNSON, OF CINCINNATI, OHIO.

TIMEKEEPER FOR TELEPHONES.

1,083,915.

Specification of Letters Patent.

Patented Jan. 13, 1914.

Application filed April 17, 1913. Serial No. 761,675.

To all whom it may concern:

Be it known that we, CLARK L. BRAUCHER and EDWARD R. JOHNSON, citizens of the United States, and residents of the city of Cincinnati, in the county of Hamilton and State of Ohio, have invented certain new and useful Improvements in Timekeepers for Telephones, of which the following is a full, clear, and exact description, reference 5 being had to the accompanying drawings, forming a part of this specification.

In the construction of a device for holding a stop watch and a record pad, which has a number of easy methods of attachment 15 or support to a telephone, wall or desk, it is desirous to employ the fewest, most easily manufactured and most easily assembled parts.

It is the object of our invention to provide 20 these features, and we accomplish it by that certain construction and arrangement to be hereinafter specifically pointed out and claimed.

In the drawings, Figure 1 is a side elevation of the device arranged to stand on a flat surface. Fig. 2 is a perspective view of the supporting means. Fig. 3 is a perspective view of the device arranged to fasten on a desk telephone. Fig. 4 is a bottom 30 perspective view of the plate. Fig. 5 represents the end plate.

The plate 1, on which are mounted the working portions of our device, is formed preferably with a depending flange 2 to 35 form a neat edge, and has the circular aperture 3 at one end for the face of a stop watch.

4. Within the aperture is a depending flange 5, which carries pins 6. On these pins 6, by means of slots in its sides, is placed 40 the circular casing 7, which receives the watch. This watch 4 is preferably provided with a check 8 and a stop and return 9 with stems therefor and crown pieces. Apertures 10 are provided for these stems in the casing 45 7. A clip 11 is mounted on the end of the plate opposite the watch face, preferably by the screws 12, and under this clip is placed the end of a record pad 13. This pad is to be ruled and marked, if desired, 50 for the convenient recording of telephone calls.

As to the use of the time-keeper,—when a long distance call is made, as soon as connection is given, the stop watch is started; 55 for all breaks in connection time is taken

out by means of the check, and when the connection is over, the total time marked upon the pad at once. We have previously applied for a patent upon a telephone time-keeper which embodies these features of 60 usefulness. Constructive differences appear in the respective plates 1 of this and 4 of that specification, but the main features of difference lie in the use of a different means of attachment and support for the plate as 65 will be now pointed out.

On the base of the plate 1 is riveted a plate 14 which carries a post 15 inclined away from the perpendicular. On this post is supported a combination standard, support and clamp, constructed of two stampings of metal 16, 16, as follows: The one edge of the two stampings is straight to stand upon a flat surface, and the other is inclined to hold the plate 1 at a convenient 70 angle when it is stood upon such surface. At the narrow end of the stampings are screwthreaded holes to receive a clamping screw 17. The plates are then bent, in opposed relation, in a half circle to form two 75 clamping members 18, 18, for the pedestal 19 of a desk telephone instrument. They are then bent straight, and then bent out to form two sides of a socket 20 to receive the post 15; bent straight again, and then out at 80 right angles to form a back support. Registering screw holes are made to receive the thumb screws 21, 21, on either side of the socket 20, and holes 22, 22, are provided on the back support whereby it may be screwed 85 to the wall.

Over the back support, is the end plate 23, with the side edges bent over at 24, 24, to slidably engage the sides of the back support. This plate serves to hold the two ends 90 of the stampings together, and to make a neat back for the supporting means.

To use the support as a clamp for a telephone, the end plate 23 is removed and the members swung on the post to a right angled 100 position. The top edge 25 of the back portion of the members is cut away at an angle equal to the angle between the post 15 and perpendicular to the plate 1. This permits it to fit against the inclined surface of the plate 1, and the position of the post is such that it will slide inside the flange 2 of the plate. To set the clamp over the telephone pedestal, the screws 21, 21, are removed and the stamping swung on the screw 17. This 105 110

is done before sliding the back inside the flange. A felt lining is preferably used in connection with the clamp portions 18, 18.

The simplicity of construction can now be seen. It is plain, without further statement, how the supporting device can be made to serve as a support or stand, or, by swinging sidewise, as a clamp for a desk telephone pedestal, or, by removing the end plate, a bracket to be screwed into the wall.

Having thus described our invention, what we claim as new and desire to secure by Letters Patent, is:—

1. An article of manufacture comprising a plate, means on the plate for holding a timing apparatus, means on the plate for holding a record pad, a post on said plate and an incline stand adapted to seat on said post.

2. An article of manufacture comprising a plate, means on the plate for holding a timing apparatus, means on the plate for holding a record pad, a post on said plate,

an incline stand adapted to seat on said post, and a clamp at one end of the stand.

3. An article of manufacture comprising a plate, means on the plate for holding a timing apparatus, means on the plate for holding a record pad, a post on said plate, an incline stand adapted to seat on said post, a clamp at one end of the stand, said clamp integral with the stand.

4. An article of manufacture comprising a plate, means on the plate for holding a timing apparatus, means on the plate for holding a record pad, a post on said plate, two plates with inclined edges, connection between said plates to form a stand, a socket between the plates for said post, said plates bent out at one end to form a clamp.

CLARK L. BRAUCHER.
EDWARD R. JOHNSON.
